UNITED STATES PATENT OFFICE

FREDERICK G. HUGHES, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT

GRINDING MACHINE

Application filed June 6, 1923. Serial No. 643,764.

This invention relates to grinding machines and is herein shown as embodied in a machine for grinding balls.

One of the common forms of ball grinders now extensively employed comprises a rotary abrading disc having ball grooves with intervening ribs and a stationary iron disc or plate having cooperating ball grooves with intervening ribs. When one of these machines is continued in use, the balls naturally wear down the grooves, particularly on the comparatively soft abrading disc, so that, at frequent intervals, the unduly projecting ribs must be faced down or dressed, so as not to interfere with grinding contact. Hitherto, an effective dressing operation has required the disassembling of the machine and the carrying of the disc to some kind of resurfacing machine. The parts are very heavy and cumbersome and the delay and interruption in the ball manufacturing operation is a source of expense and complaint.

An object of the invention therefore is to provide a machine which will avoid the above noted and other objections as by resurfacing the abrading disc in its normal grinding position.

Another object of the invention is to provide a simple and effective dressing device which can be easily attached to existing grinders.

Still another object is to provide an improved dressing device which will be readily accessible for actuation and not interfere with the normal operation of the grinder on which it is used.

To these ends and also to improve generally upon devices of the character indicated my invention consists in the various matters hereinafter described and claimed.

Referring to the drawing, Figure 1 is a radial section through a portion of a ball grinder, showing the dresser attached.

Figure 2 is an end elevation of the dressing device.

Figure 3 is a top plan view of the dressing device, and

Figure 4 is a detail section of the dressing tool and its attaching means.

The numeral 10 designates a disc or plate to which is clamped a ring or disc 12 of abrading material having concentric ball grooves 14 with intervening ribs or lands 16. The disc 10 is threaded on the end of a hollow spindle 18 which is driven at high speed during the grinding operation. In axial alignment with the first rotary disc is a stationary disc or plate 20 carrying a ring, plate or disc 22, preferably of cast iron. The ring 22 has a series of ball grooves 24 with intervening ribs cooperating with the similar ball grooves and ribs on the rotary disc.

Extending through the stationary disc, parallel to the axis of the rotary disc, is a series of shafts 26 which are arranged preferably in a radial plane, each shaft having a diameter approximately equal to the width of a rib and having its end face opposite to a rib of the rotary disc. Each shaft can rotate and is also slidable to a limited extent, there being fixed at the end of the shaft near the circumference, or at least eccentrically, a dressing tool 28, preferably a chip diamond. The diamond is carried substantially in the plane of the end face of the shaft by the end of a pin or pencil 30 slidable in a diagonal opening 32 through the shaft 26 and intersecting the end face at the periphery. The pin 30 can be fixed in the desired adjusted position by a screw 34 threaded in the end of the shaft 26. Each shaft 26 is enlarged at one end and is rotatably supported in a carrier 36, an integral collar 38 on the shaft engaging one side of the carrier and a washer 40 fixed to the end of the shaft by a screw engaging the other side of the carrier.

Cut in the enlarged portions of the shafts are gear teeth 42 meshing with worms 44 on a shaft 46 extending at right angles to the shafts 26 and at one side of them. A hand wheel 48 at the end of shaft 46 is rotated to effect, through the gearing, rotation of the shafts 26. This causes the dressing tools 28 to traverse the width of the ribs 16 during rotation of the abrading disc 12, thereby facing said surfaces.

When beginning this operation, all of the

shafts are slid, to the left, as shown in Figure 1, to bring the dressing tools into engagement with the ribs and this is accomplished by sliding the carrier 36. The carrier has a tongue 50 slideable in a dove-tailed way 52 in a bracket 54 bolted to the stationary plate 20. A projecting lug or flange 56 on the bracket is slotted as shown at 58 and a bolt 60 passing through the slot and threaded in the bracket 54 serves to hold the carrier in the adjusted position. When the dressing operation is completed, the shafts are all brought back to their original position with the ends of said shafts in alignment with the surfaces of the ribs on the disc 22 through which they pass.

Although the invention has been described and illustrated by reference to a specific mechanism, it should be understood that, in its broader aspects, the invention is not necessarily limited to the particular mechanism selected for illustration.

I claim:

1. In a machine comprising a rotary abrading disc having ball grooves with intervening ribs and a stationary disc having complementary ball grooves with intervening ribs, the combination of a shaft extending through each of said last mentioned ribs between adjacent grooves and arranged to engage a rib on the rotary disc, a dressing tool eccentrically carried by each shaft, and means for rotating the shafts to resurface the ribs, substantially as described.
2. In a machine comprising a rotary abrading disc having ball grooves with intervening ribs and a stationary disc cooperating with the rotary disc, the combination of a plurality of shafts extending through said stationary disc, means to effect an endwise adjustment of said shafts to cause them to engage the ribs on the rotary disc, a dressing tool carried by each shaft, and means for rotating the shafts to resurface the ribs, substantially as described.
3. In a machine comprising a rotary abrading disc having ball grooves with intervening ribs and a stationary disc cooperating with the rotary disc, the combination of a carrier attached to said stationary disc, shafts journaled in said carrier and extending through said stationary disc, a dressing tool carried by each shaft, and gearing on the carrier for simultaneously rotating the shafts to resurface the ribs, substantially as described.
4. In a machine comprising a rotary abrading disc having ball grooves with intervening ribs and a stationary member, the combination of a carrier attached to said stationary member, shafts journaled in said carrier and extending through said stationary member, a dressing tool on the end of each shaft, means for adjusting the carrier to cause the dressing tools to engage the ribs

on the rotary disc, and means on the carrier for rotating the shafts, to resurface said ribs, substantially as described.

5. In a machine comprising a rotary abrading disc having ball grooves with intervening ribs and a cooperating stationary member, the combination of a carrier attached to said stationary member, shafts journaled in said carrier and extending through said stationary member, dressing tools on the shafts, gear teeth on the shafts, a shaft having gear teeth meshing with the gear teeth on the first mentioned shafts to rotate the latter, and means for adjusting the carrier to cause the dressing tools to come into engagement with the ribs on the rotary disc, substantially as described.

6. In a grinding machine having a grinder and means for rotating the grinder, a series of shafts extending parallel to the axis of the grinder and arranged in a radial plane, a dressing tool eccentrically mounted on the end of each shaft, and means for rotating the shafts to carry each dressing tool over a portion of the surface of the grinder, substantially as described.

7. In a machine comprising a rotary abrading member having concentric ball grooves with intervening ribs and a parallel stationary member having cooperating and uninterrupted ball grooves with intervening ribs, and mechanism for dressing the ribs of the rotary member without moving either member from grinding position and comprising rotary operating shafts extending through the stationary member and the intervening ribs between the grooves to leave the grooves uninterrupted, a dressing tool mounted at the junction of the end face and periphery of each shaft, and means for rotating the shafts; substantially as described.

8. In a machine comprising a rotary abrading member having ball grooves with an intervening rib and a stationary member cooperating with the rotary member, a shaft extending through said stationary member and journaled on an axis parallel to the axis of the rotary member, the shaft having a diameter approximately equal to the width of the rib and having its end face opposite to the rib, a dressing tool eccentrically carried at the end face of the shaft, and means for rotating the shaft; substantially as described.

In testimony whereof I hereunto affix my signature.

FREDERICK G. HUGHES.
